United States Patent Office

Des. 196,156
Patented Aug. 27, 1963

196,156

FILM VIEWER

Clarence S. McClellan, Los Angeles, Calif.
(1237 5th St., Santa Monica, Calif.)

Filed Apr. 9, 1963, Ser. No. 74,358

Term of patent 14 years

(Cl. D61—1)

FIG. 1.

FIG. 2.

FIG. 3.

FIG. 4.

FIG. 5.

FIG. 6.

FIGURE 1 is a front elevational view of a film viewer, showing my new design;

FIGURE 2 is a rear elevational view thereof;

FIGURE 3 is a side elevational view thereof of the left-hand side as viewed in FIGURE 1;

FIGURE 4 is a top plan view thereof;

FIGURE 5 is a side elevational view thereof showing the side opposite to that shown in FIGURE 3; and

FIGURE 6 is a bottom plan view thereof.

The essential features of my design are shown in full lines on the drawings.

I claim:

The ornamental design for a film viewer, substantially as shown and described.
